Richard McFadyen, Upper Montclair, N.J., assignor to Ketcham and McDougall, Inc., Roseland, N.J., a corporation of New Jersey

Filed Sept. 6, 1962, Ser. No. 71,579

Term of patent 14 years

(Cl. D74—1)

FIG. 1

FIG. 1 is an end view of a desk pad with memorandum clip showing my new design as viewed from the top of FIG. 2;

FIG. 2 is a top plan view thereof, the dotted line showing of a pad in this figure being for illustrative purposes only; and

FIG. 3 is a side elevational view thereof, the opposite side not shown being a replica of that shown.

I claim:

The ornamental design for a desk pad holder with memorandum clip, as shown and described.
